TO HARRY HOLLEY, OF DETROIT, MICHIGAN.**METAL MOLD.**

Application filed August 19, 1925. Serial No. 51,083.

The object of this invention is to provide improved means for casting cast iron pistons in metal molds. Specifically the object is to provide means whereby the casting when it is ejected from the metal mold is of substantially uniform temperature. When the casting is not of uniform temperature the time during which the casting remains in the mold is prolonged in order to prevent the premature discharge of the casting.

The ideal time for ejecting the casting is the earliest possible moment at which the casting is sufficiently set so that it will not be deformed during the ejection of the casting from the mold. Hence temperature uniformity is desirable for various reasons.

Furthermore, in order that the advantages of a metal mold may be secured it is desirable that the rate of cooling of all parts of the piston shall be the same. This uniform rate of cooling is best obtained by placing the skirt of the piston down in the mold and the head of the piston up, because the head of the piston has a greater amount of metal in it and therefore tends to remain molten longer than the skirt which is relatively thin.

On the other hand, that part of the casting which is uppermost in the mold tends to cool faster for the reason that the iron there comes to rest opposite a portion of the mold over which iron has not flowed whereas the iron in the lower portion of the mold comes to rest opposite a portion of the mold over which the iron has flowed on its way to fill the upper portion of the mold. By thus obtaining uniform cooling rates the percentage of combined carbon will be uniform throughout the piston, which will enable the ideal heat treatment to be applied so as to produce the desired composition as far as combined carbon is concerned.

Figure 1 shows the face of the mold in elevation, the casting in the mold being shown in cross section.

Figure 2 shows a cross sectional plan view taken on the plane 2-2 of Figure 1.

Figure 3 shows a cross sectional elevation taken on the plane 3-3 of Figure 1. In the figures, A is the sprue, B is the gate leading therefrom; C is an annular groove in the mold which distributes the iron equally to the four gates, two of which, R and S, are shown in Figure 1 and the passage for which is shown at T in Figure 3.

Pistons can be successfully cast with only two of the gates located as is the gate T. That is to say, the gate C would merely be a half circle with two gates acting as prongs connecting the sprue A with the piston matrix. However, there are some advantages in having 4 gates rather than 2, as the 4 gates serve with the annulus C to hold the skirt round.

In order to reduce leakage of metal grooves P and Q are provided. In order that the air may escape conveniently the mold cavity is inclined slightly (7°) and the riser R provided at the upper corner. The ears LM are provided to support wings which will direct cooling air onto the backs of the molds which are provided with fins H.

The thickness of the wall of the piston is preferably about $\frac{5}{8}$ ". The core E is mounted on the ledge U, which groove serves both to support the core and center it within the mold. The core is preferably arranged so that the piston bosses lie in the plane in the parting line between the two halves of the mold, as there is more metal at this point than elsewhere, and therefore the metal in the boss is cooled at a fairly uniform rate, whereas if it is turned at 90° to this position the piston boss will come opposite the back of the mold where there is no extra metal except that due to the fins H.

One of the additional advantages of this construction is that in addition to the piston being ejected with a uniform temperature throughout its mass, the dirt that is left in the mold is easily cleaned out as the entire lower portion of the mold is open after the casting has been ejected.

What we claim is:

In combination with a sectional mold adapted for the casting therein of an automobile type piston head up, a cylindrical dry sand core within said mold, a shoulder on said mold whereby the core is located concentrically within said mold and prevented from rising therein under the ferrostatic head of the metal cast therein, an annular groove located immediately above

said supporting shoulder, a plurality of gates connecting said groove to the matrix of the piston skirt, a sprue adapted to feed iron to said groove.

In testimony whereof we affix our signatures.

JOSEPH L. DOSTAL.
